UNITED STATES PATENT OFFICE.

NILS EMEL NORSTROM, OF CHICAGO, ILLINOIS.

LOCK-OUT TELEPHONE SYSTEM.

1,001,070.

Specification of Letters Patent. Patented Aug. 22, 1911.

Application filed June 6, 1910. Serial No. 565,254.

To all whom it may concern:

Be it known that I, NILS EMEL NORSTROM, a citizen of the United States, residing at Chicago, in the county of Cook and State of Illinois, have invented certain new and useful Improvements in Lock-Out Telephone Systems, of which the following is a specification.

My invention relates to improvements in lock-out telephone systems, and has for its general object to provide a simple and efficient system of the character described.

Many special objects are attained in the embodiment of my invention, and will become apparent from the following description, but one of the salient objects of the invention is to provide mechanism whereby in calling a desired party upon a party line, a positive disabling operation is automatically effected with respect to the apparatus of each of the parties on that line, except the one desired, thereby to prevent any party save the desired party from receiving the call, or from effecting an operative connection of his telephone apparatus with the line until the disability is removed by the action of the central operator.

A further special object of my invention is to provide an arrangement whereby it is substantially insured that the step-by-step apparatus, at the stations of the various subscribers, in a line, shall always be in appropriate step relation.

Another object is to provide at the subscriber's station step-up apparatus arranged to perform its full cycle of operations and return to normal or starting position during the making of the outgoing call, so that no special operation on the part of the central operator is required to condition the subscriber's apparatus for subsequent in- or out-going calls.

In the drawings, Figure 1 is a diagrammatic view of the circuits and apparatus; Fig. 2 is a detail of a switch in one operative position; Fig. 3 is a diagram of the circuits alone; and Figs. 4, 5 and 6 are diagrammatic views showing the relation between the mechanical parts of the subscriber's step-up device.

Referring to the drawings, 10 and 10' indicate the line wires of a metallic party circuit, running into suitable switch-board connections, generally indicated at 11, the line wires being connected to the switch arms, 12 and 12', of a cut-off relay, 13, said switch

arms being normally connected with the contacts of the line relay, 14, connected with the central battery, 21, and controlling the line signal, 15. When the cut-off relay, 13, is energized, the switch arms, 12 and 12', are moved to connect the line wires, 10 and 10', with the tip and sleeve contacts, 16 and 16', of a jack, J, the test ring, 16'', whereof is grounded through the cut-off relay 13. It will be understood of course that the usual multiple jack arrangement is employed.

20 indicates in general a central station cord circuit equipment, of any suitable customary form except in the features of the ringing circuit connections hereinafter referred to. In such cord circuit arrangement, as shown, 21 indicates a central battery having one terminal grounded and bridged between the tip strand, 22, and sleeve strand, 22', leading respectively to the tip and sleeve of the answering and calling plugs, P and P'.

23 indicates the strand of the cord connecting the rings of the plugs and including 80 the supervisory lamps, 24, the supervisory relays, 25, which control the lamp shunts, 26, being included in the sleeve strand, 22'.

27 indicates, in general, a combined ringing and listening key, arranged for operation at pleasure to cut in the operator's set, 28, or on the other hand, to open the cord circuit and close switches 29 and 29', for bridging the ringing-current generator across the tip and sleeve connections of the 90 calling plug, P'. The anvils of the switches 29 and 29' connect with the ringing circuit wires, 30 and 30', extending to a suitable source of supply of alternating current. Specifically, ringing current is supplied to 95 the wires 30 and 30' by a battery, 31, through the intermediary of a pole changer, 32, which normally operates continuously, the operating magnet, 33, thereof being connected in a suitably energized circuit, 34, 100 provided with a switch, 35, to be hereinafter described, said switch being normally closed.

In general arrangement and construction, the parts thus far described are intended to typify any suitable line, cord circuit, and ringing arrangement, the particular form and arrangement of these devices shown being selected for simplicity and fullness of disclosure, and forming no part of my invention.

At the central station, I provide in addition to the usual cord circuit and ringing

circuit connections, as described, means by which the central operator, in effecting a call, may insure that the alternating ringing current generator starts its operation by im-
5 pressing a definite polarity upon the ringing circuit, thereby to insure that at the commencement of the operation, the polarized step-up devices, hereafter described, may start in unison in proper step. I also pro-
10 vide at the central station, instrumentalities arranged to operate in harmony with the step-by-step devices of the several sub-
scribers' stations and governing the condition of various branches of what I will term
15 the controlling circuit, distinct from the line circuit, and serving to bring certain controlling instrumentalities at each sub-
scriber's station within the control of the central operator.
20 In the specific construction shown, 40 indicates in general a step-up device at the central station comprising as its moving element a ratchet wheel, 41, carrying a wiper, 42, arranged to sweep over a bank
25 of contacts, 43. This contact bank has at opposite ends elongated contacts, 43^a and 43^b, and intermediate contacts, 43^c, in number equal to the maximum number of stations on the party line. The ratchet wheel
30 is arranged to be advanced by an active pawl, 44, carried by the armature, 45, of a polarized electromagnet, 46, and is also acted upon by a holding pawl, 47. The ratchet carries a pin, 48, for releasing a
35 latch, 49, which is provided with a nose, 49', arranged to receive and retain under tension and in electrical connection therewith a contact spring, 50, when the latter is depressed. The latch 49 will hold said
40 spring 50 in depressed position, in electrical contact with the latch nose until the pin 48 strikes the latch and releases it after a pre-
determined operation of the ratchet wheel
45 41. The latch 49 is electrically connected to the frame, and from a frame binding post, 51, connection is made by wire 52 with the ringing circuit wire, 30', the spring 50 having connection by wire 54 with the operating magnet 46, and thence by wire 55
50 to the second ringing circuit wire, 30. Thus, whenever the spring 50 is brought into electrical connection with the nose, 49', of the latch 49, the polarized magnet 46 is bridged across the ringing circuit to receive
55 the alternating ringing circuit current, thereby to vibrate its armature, 45, and through its pawl, 44, to advance the ratchet wheel. For appropriately depressing the spring 50 into engagement with the latch 44
60 and to perform other functions, I provide an electromagnet, 57, the armature, 58, of which, when attracted, serves to depress the spring 50 into its aforesaid electrical connection with the latch, and at the same time
65 through complementary engaging parts, 59,

on the armature and the holding pawl 47, to withdraw said holding pawl from engagement with the ratchet, 41. Also said armature 58 serves when in normal raised position to retain closed the switch 35, which governs the operating circuit of the pole changer magnet, 33, so that when the armature 58 is attracted, said circuit is opened. This electromagnet, 57, is connected by wire 60 with the wire 55, and by wire 61, preferably including a small battery, 62, through a normally open switch, 63^a, of a starting key, 63, and wire 64, with the ringing circuit wire, 30. Thus, whenever the switch 63^a is closed, a circuit is established from the battery 62, by wire 61, electromagnet 57, wire 60, 55, 30, 64, and the closed switch 63^a, back to the battery, to energize the starting magnet, 57.

The starting key, 63, is provided with an additional switch, 63^b, having one branch connected, as by wire 67, with a battery 68, the opposite terminal of which is grounded as at 69, the remaining wire, 70, from said switch 63^b having connection in common, as at 70^a and 70^b, to the two terminal contacts, 43^a and 43^b, of the step-up device. The starting key, 63, is so constructed that when fully depressed it closes both the switches 63^a and 63^b, and when released from maximum depression returns to a mid-position in which switch 63^a is open while switch 63^b remains closed.

Each of the contacts 43^c of the step-up device has a connection, 71, including a normally closed selector switch 72 to the wire 67, each switch 72 preliminarily settable—that is being capable of being set in open position by a selector key, 73, before the call is transmitted. These selector keys, 105 as will hereafter be shown, control the selection of the desired station on the party line. Obviously, when the step-up device makes its forward movement, during the first few steps its wiper, 42, remains in connection with the elongated contact 43^a, so that the sleeve side, 30', of the ringing circuit has an energized ground connection through the wire 52, frame, spring 41, and connections 43^a, 70^a, 70, 63^b, 67, battery 68, 115 69, ground, and thereafter between the extremes of every advancing step, the wiper arm 42 makes connection with one of the contacts of series 43^c to effect a similar energized connection by path 52, frame, 42, 120 43^c, 71, 72, 67, battery 68, 69, ground, unless the switch 72 in such possible connection be opened by the action of the operator. It may here be observed that, in passing over contacts 43^c, the wiper 42 dwells, 125 between steps, out of engagement with the contacts. Thus, in general, the station apparatus provides in connection with the ringing circuit, means whereby the operation may be started by impressing a definite 130

polarity upon the ringing circuit to occasion all polarized instruments and the condensers associated with the ringing circuit to receive a definite charge, thereby to insure a uniform starting of all the polarized devices; and then the alternating current causes the operation of the polarized relay 46 to operate the step-up device, 40, at the central station, the first few steps maintaining an energized ground connection with one side of the ringing circuit, and each step thereafter momentarily effecting such a connection, there being provided means (in the form of the keys 73) whereby the central operator may prevent the establishment of such energized ground connection upon the movement of the step-up device over any selected contact of the series 43^c.

At each subscriber's station, I provide the usual subscriber's instruments, to wit, the talking set and ringer, and a polarized operating relay for connection across the metallic ringing or talking circuit, and I provide controlling devices including a relay, capable of ground connection with the appropriate side of the line, for actuation by current supply from the grounded central battery, 68, or the grounded talking-circuit battery, 21, as the case may be. Specifically, the station apparatus which I employ includes a polarized relay, 80, the armature, 81, of which operates the step-up pawl, 82, for the step-by-step ratchet wheel, 83, which may operate harmoniously with the step-by-step device, 41, at the central station. A retaining pawl, 85, is provided for the ratchet wheel 83, controlled as to its release by the armature, 87, of a controlling magnet, 86, said holding pawl being preferably mounted upon said armature so that when the armature is moved to fully retracted position the pawl is disengaged from the ratchet. In order that the releasing operation of the pawl 85 may be timed by the ratchet itself, I provide an armature latch, 88, shown as a pivoted bell-crank lever, normally raised by a pin, 89, on the ratchet wheel 83, to position out of engagement with the armature 87, and adapted to be raised again by a pin 89' into such disengaging position after a predetermined excursion of the ratchet wheel. The latch nose 88' is so disposed that when the armature is latched forward thereby, the spring holding pawl 85 is operatively related to the ratchet, yet the armature 87 is allowed a sufficient play toward and from its magnet to perform its mechanical controlling operations, hereafter to be described, according as the magnet is energized or deenergized, without interference by the latch.

The step-up wheel 83 is arranged to control a governor member, 90, which, according to its different positions, governs the

ability of the apparatus at the particular station to receive a call as a result of its cycle of operation, which is incident to every call made on the line. Specifically, the governor 90 is shown as a pivoted latch having 70 an arm, 91, provided with a pin, 91^a, coacting with a cam rib, 93, upon the wheel 83. Normally, as shown in Fig. 1, the pin 91^a of the arm 91 is free from the cam 93, and the governor stands in a position determined 75 by the engagement of a spring, 94, mounted upon its tail, with a stop, 95. The cam rib 93 is so disposed that as the wheel advances through an arbitrary series of preliminary steps, a cam portion, 93^a, of the rib, forces 80 the controller down to what I may term its operative plane; then through a succession of steps, (equal to those made by the step-up device, 41, at the central station in sweeping contacts 43^c) the cam rib is concentric, as at 85 93^b, and then, beyond such concentric arc, it has a further outward deflection, 93^c, sufficient to depress the governor so as to bring a switch spring, 97, carried thereby, into contact with a stationary contact, 98, which, as 90 hereafter described, is in the ringing circuit. At a suitable position, different for each station on the line, the cam rib has an opening, 93^x, made therein, through which the pin 91^a may pass if the controller 90 is left 95 free to rise under the tension of its spring, 94, when said opening 93^x registers with the pin 91^a. The time in which such registry of the pin with the opening occurs at such station harmonizes or is in step with the 100 time at which the wiper 42 of the central station step-up device registers with the contact of the series 43^c, corresponding with that particular subscriber's station on the party line; that is to say, on a ten party 105 line, party number seven has the notch 93^x in the cam rib of his ratchet wheel come into registry with the pin 91^a when the concentric arc of said rib has moved forward seven steps with reference to the pin, and at which time, as will hereafter be more fully explained, the central station step-up device will bring its wiper into connection 110 with the seventh contact of the series 43^c. In connection with the governor, I provide a detent for locking it in lowered position, or permitting it to rise through its appropriate aperture 93^x, according to the condition of the electromagnet 86. Thus, I provide upon the extremity of the governor 115 lever 90, a latch nose, 90^a, and arrange for coöperation therewith a detent, 100, preferably carried by a spring constituting one of a spring-contact stand hereafter described. This detent 100 is arranged to latch the governor in lowered position by its spring action, but is controlled by the armature 87, so that when the latter is fully attracted or "frozen," the detent 100 is moved to inoperative position, so that it can 120 125 130

not restrain the governor 90 against upward movement. Specifically, the detent 100 is mounted upon a contact spring, 101, back of which are arranged two other contact springs, 102 and 103, the three springs being normally separated, but arranged to be brought into electrical union whenever the detent 100 is engaged with and locks the nose, 90^a, of the governor 90. Mechanically 10 moving with but insulated from the spring 101, is a contact spring, 105, arranged to receive a laterally off-set and forwardly extending contact arm 87' of the armature 87 in contact therewith only when the armature is either frozen or latched by part 88', said spring, 105, normally closing connection with an anvil, 106, when the armature is fully retracted. Thus, when the governor 90 is raised and armature 87 is fully retracted, the contact springs stand in the relation shown in Fig. 1, but when the armature 87 is frozen, connection between springs 105 and 106 is opened, connection is established between springs 101, 102, and 103, 25 and the detent 100 is moved out of the path of the nose, 90^a, of the governor 90.

The talking set of the subscriber is shown as comprising transmitter 110, the receiver 111, switch hook 112, and coil 113. The 30 talking circuit depends for its closure upon the closure of switch 101 and 102, and the standing of the ratchet wheel in normal condition. Thus the talking circuit includes wire 115, extending from wire 10' to the 35 frame of the mechanism, with which are electrically connected various parts, including the wheel 83, a pin 117 on said wheel serving, when the ratchet is in normal position, to make electric contact with a stop 40 spring, 117', connected by wires 118 and 119 with the spring 101, the spring 102, next thereto, having connection by wire 120 with the transmitter 110, and the switch hook 112 being connected by wire 121 direct to the 45 line wire 10.

The ringing circuit is controlled by the switch 97-98, having connection by wire 122 to the bell or ringer, 123, which is connected by wire 124, through a condenser 125, to wire 121 and thence to the line 10. The 50 operating relay 80 has its coils bridged between the frame connection 116 and wire 124, so that it is bridged directly across the line through the condenser 125. The controlling magnet 86 has its coil grounded on one side, as at 130, its other terminal being connected by wires 131 and 132 with the subscriber's key, 133, which when depressed makes a lower contact connecting it with 55 wire 134, tied to wire 118. Thus, by depressing key 133, the subscriber may, if the ratchet wheel 83 is in normal position, establish a ground circuit, 130, 131, 132, 133, 134, 135, 118, 117', 117, frame, 116, and 115, 60 to line wire 10'. As a refinement, wire 135

may have therein a magnet, 136, the armature of which carries a busy target, 137, arranged to show through a casing aperture, 137^a, when the armature is attracted. An upper contact, 138, for said key 133 is connected by wire 139 with the anvil of a switch 140, the moving member of which is carried by the armature 81 of the operating magnet 80, so as to close every time the armature of the polarized relay makes an 70 active or forward stroke. The wire 131 likewise has connection by wire 141 with the spring 105, and the two outer springs, 103 and 106, are connected together, as at 142.

In general, it will be observed that the 80 circuits which I have indicated in heavy lines, in Fig. 1, are the bridged connections of the operating magnet, the talking set, and the ringer, while the lighter-lined wiring is incident to the establishment or variation of a ground circuit for the controlling magnet 86.

I will now describe the operation of the apparatus.

Calling-in.—Subscriber removes receiver 90 from switch hook and presses key 133. A ground circuit for the line relay 14 is established from the central grounded battery 21 through the line relay 14, line 10', connection 115, frame ratchet wheel, contact 117, spring 117', wires 118 and 135, magnet 136, switch 133, wires, 132, 131, magnet 86, and wire 130, to ground. The central battery current, through the high resistance line drop, is insufficient operatively to energize 100 the magnet 86 or magnet 136, but it energizes the line relay 14 sufficiently to cause the line signal to operate in the usual manner. Now, when the operator plugs in, the line relay 14 is cut off in usual fashion, and the central battery supplies current to the line 10' through only the resistance of the cord circuit, which sufficiently increases the current supply to the line so that the magnet 86 is energized, and attracts its armature, as does also the magnet 136. When the armature 87 is attracted, the switch 133 is shunted through the connection 141, 105, 87', to the frame, so that when the key 133 is released by the subscriber as soon as he 115 hears the voice of the central operator, the operating magnet 86 is maintained energized, thereby to hold closed the contacts 101 and 102, through which the talking circuit heretofore described, is established. Now, as long as the plug remains in the jack, this condition maintains, and the calling subscriber may talk or listen. Should any other subscriber, however, endeavor to 120 get the line, the closing of his switch, 133, would divert part of the central battery current, to the parallel ground connections at his station thus established, causing magnet 136 to attract its armature to display 125 the busy target immediately, but the mag-

net 86 is such that this partial current strength of the central battery is insufficient to attract the armature 87, and the intruder's receiver remains dead. Obviously, 5 however, the cutting down of battery current through the magnet 87 of the connected subscriber does not destroy his connection, as but little current is needed to maintain the armature 87 frozen.

10. It will be observed that the step-up apparatus of the calling subscriber is not advanced from its normal position by reason of the ingoing call, so that the closure of the talking circuit at the station of the calling 15 subscriber is dependent solely upon the maintenance of the armature 87 in attracted position. Therefore, it will be seen that as soon as a call is completed and the central operator removes the plug from the jack, 20 the movement of the contact springs 12-12' of the cut out relay 13 from the line-closing position to normal position, momentarily disconnecting the subscriber's station from any source of current supply, breaks 25 the circuit for the operating magnet 86, allowing the armature 87 to become retracted, and thus returning all parts to normal condition.

Calling-out.—When the central operator 30 calls out upon a party line to get, let us say, subscriber at station number seven on the line, the operation of the system is as follows: First the central operator plugs in with the calling plug, P'. This produces no 35 effect at any station on the line. Then she depresses or sets the seventh key, 73, which locks in depressed position, opening the connection between the grounded operating battery, 68, and the seventh contact of the series 40 of 48°, for the central station step-up device, 40. Then she depresses the starting key, 63, and throws the ringing key, 27, to the ringing side. The full depression of the starting key, 63, results in the breaking of the circuit 45 of the pole-changer magnet, 33, and prepares the central station step-up device, and the step-up devices at all of the subscribers' stations on the connected line for operation. Specifically, the full depression of the starting 50 key, 63, closing switches, 63^b and 63^a, establishes for the magnet 57 the following circuit: 62, 57, 60, 55, 30, 64, 63^a, 61, so causing magnet 57 to attract its armature, which 55 depresses contact spring 50 into latching engagement and electrical connection with the latch 49 of the central station step-up device, pulling out the holding pawl from engagement with the ratchet wheel 41 to permit the return of the ratchet to normal position from the terminal advanced position which may previously have occupied, and opening the switch 35. The opening of the switch 35, breaks the circuit of the pole changer magnet, 33, so that the pole changer 60 stands quiet in the position indicated in

Fig. 1, impressing upon the ringing circuit the connected line and the devices bridged across said circuit, a definite polarity. Thus the condensers, 125, at the several stations are definitely charged and the armatures of the polarized operating relays, 81, are definitely brought to position to retract their operating pawls, 82. When the starting key, 63, has thus been held depressed for a moment, it is released and returns to mid position (shown in Fig. 2) in which it retains closed the switch 63^b, and opens the switch 63^a. This opens the circuit for magnet 57, heretofore described, permitting the armature 58 to rise, so that the holding pawl 47 is brought to operating position, the spring 50 is left engaged under the latch nose 49' and switch 35 is closed. The closure of switch 35 conditions the automatic pole changer for operation and it immediately begins vibration to send out impulses over the ringing circuit from the battery 21. Such alternating impulses act upon the polarized relays 46 and 80 at the central station, and the subscribers' stations respectively causing them 80 to operate in harmony. The circuit for the operating magnet 46 is established as follows: Battery 31, pole changer contacts, 30', 52, 51, 49, 49', 50, 54, magnet 46, 55, 30, back through the pole changer contacts to battery. The parallel connections of the magnets 80 at all subscribers' stations extend from the ringing circuit wires 30, ringing switch 29', 22', plug sleeve, contact 16', wire 10', connections 115, 116, magnet 80, wire 124, 95 condenser 125, wires 121 and 10, tip contact 16, and its appropriate plug contact, tip strand 22, switch 29, back to wire 30. The armatures of magnets 46 and 80 are arranged to operate oppositely, however, making their advance movements on opposite phases of the current, so that the step-up device 83 attains and is dwelling in a step-position when the ratchet 43 sweeps its wiper 42 over the contact 43^c corresponding 100 with that position.

With the first forward step of the armature 81 of the operating magnet 80, at each subscriber's station, an energized circuit for the operating magnet 86 is closed 115 as follows: ground, 69, 68, 67, 63^b, 70, 70^a, 42, 41, 51, 52, 30', 29', 16', 10', 115, 116, 140, 139, 138, 133, 132, 131, magnet 86, 130, ground. Thus at each subscriber's station on the party line, the armature 87 is attracted by its magnet 86, throwing the ratchet-holding pawl 85' to operative position where it is immediately latched by the part 88, as the pin 89 on the first step may move to latch-releasing position, so that the latch nose 88' drops back of the attracted armature 87. The armature 87 will obviously remain fully attracted as long as the ground circuit above described is maintained, and this circuit is maintained during 120 125 130

the several steps that wiper arm 42 is on terminal contact 43^a, during which said steps cam-rib-portion 93^c on the subscriber's ratchet forces the controller 90 down to 5 position to latch springs 101, 102, and 103, and be latched by detent 100 on said spring 101.

Now, on one phase of an impulse, ratchet 83 steps forward to bring the notch 93^x in the 10 cam rib 93, at station of party number 1 in register with the pin 91^a of the controller 90, and on the other phase of the same impulse, ratchet 41 at the central station steps forward to sweep wiper 42 over the first contact of series 43^c. Switch 72 connected with 15 this first contact 43^c being closed, the energized circuit for magnet 86 is closed by the path 130, magnet 86, 131, 141, 142, 105, armature 87, frame, 116, 115, line 10', sleeve 20 strand 22', 30', 52, 41, 42, 43^c (first contact), 71, 72 (first switch), 67, battery, 68, 69, ground. Thus, at each station, magnet 86 25 fully attracts its armature, releasing detent 100 from controller latch nose 90^a, and so all of the controllers are freed to rise. At station 30 No. 1, the controller 90, thus freed, springs upward, and its pin 91^a passes through the registering opening 93^x in the cam rib 93, but at all other stations, the cam rib being solid at the position in register with the pin 91^a, the governors at such other stations remain depressed.

The springing of the governor 90 to raised position at station No. 1 disables said station to receive a call, as will hereafter become apparent, as from this point on, the pin 91^a at station No. 1 travels on the inside of the cam rib 93, and the governor cannot be depressed to position to be latched by the 40 detent 100, which operation is necessary, as will hereafter become apparent, to the completion of a call at the desired station.

At each forward step until the seventh, the operation last described is repeated with 45 respect to the governors at the successive stations, until the seventh station is reached, when the magnet is deenergized by the resting of the wiper 43 between the sixth and seventh contacts of series 43^c, the armature 50 87 of the operating magnet 86 of course standing back against its stop 88', and the detent 100 accordingly engaging the nose 90^a of the governor. Thus, when the ratchet 83 steps forward to bring notch 93^x opposite 55 the pin 91^a, the pin cannot escape therethrough unless the detent 100 is removed from the governor nose. Now, the wiper 42 sweeps over the seventh contact of 43^c, but the seventh switch 72, having been opened 60 by the operator, no circuit is established for the magnet 86, and consequently the armature is not attracted and the detent 100 is not removed from the latch nose of any governor. Then the ratchets at all the 65 stations step forward to eighth position, and

the solid portion of the cam rib of the ratchet at station No. 7 again confronts the pin 91^a so that when the ground circuit for magnet 86 is again made on the eighth contact of series 43^c, only the governor at station No. 8 is disabled, the governor at station No. 7 having passed without the disabling operation the only point at which it can be disabled.

When the tenth contact has been passed, 75 all of the stations except station No. 7 have had their governors disabled, and at the central station wiper 42 comes to rest upon the terminal contact 43^b, thereby finally energizing all of the relays 86 at the several 80 stations. The tooth arrangement of the ratchet 83 at each subscriber's station enables it to advance a few steps farther, so that the cam portion 93^c gives an extra depression to the governor 90 at station No. 7 (the only 85 governor that then remains on the outside of the cam), so causing spring 97 to contact with contact 98 and bridging the ringer 123 across the line 10—10' through the connections 121, 125, ringer 123, 122, 98, 97, frame, 90 115. Thus, only the ringer at the station of the desired subscriber is actuated by the continued application of the ringing current.

Now, when the central operator has rung the party sufficiently long, she releases the 95 ringing key, 27. This disconnects the source of alternating current supply from the line and also momentarily disconnects the central battery from the called line. Accordingly, no central station source of supply is 100 available to energize magnet 86, and the holding latch, 88, having been lifted to disengaging position by the pin 89' the armature 87 at each station falls back to fully 105 retracted position, moving the holding pawl 85 to disengaging position, and freeing the ratchet 83 for return to normal or starting position. In this movement the ratchet at the called station will lead the others, as the cam action of part 93^c acts to hasten the 110 return of the ratchet at the said called station.

When the armatures drop back to fully retracted position the springs 101, 102, and 103, of all of the stations except No. 7 are 115 opened, those at station No. 7 being latched closed by the nose 90^a. At none of the stations is the controlling magnet now capable of being again energized, until the ratchet is turned to normal position. When 120 such return is completed, the apparatus at station No. 7 only is conditioned for the energization of the magnet 86, through a circuit as follows: grounded line battery, 21, sleeve strand 22', line 10', 115, 116, 117, 117', 125 118, 119, 101, 102, 103, 142, 106, 105, 141, 131, magnet 86, 130, ground. It will be observed that this circuit includes connections 117 and 117', which are made only when the ratchet is in normal position and that the 130

said circuit includes also switches 101, 102, and 103, which are closed, under the conditions assumed now to exist, only at the station No. 7. Consequently at station No. 7, 5 the armature of magnet 86 is attracted, and will remain in frozen position as long as the central station connection is maintained. When it moves to frozen position, the armature 87 releases the detent 100 from the 10 governor nose 90, so that the governor 90 rises to its normal position shown in Fig. 1, thereby restoring all the operating parts controlled by the ratchet 83 to normal condition and leaving the circuit connections of the 15 called subscriber closed only by the armature 87 which is free to return to fully retracted position as soon as the central connection is broken.

Now, when the called subscriber removes 20 his receiver from the hook his instrument set is bridged between the line wires through the connections 115, 116, 117, 117', 118, 119, 101, 102, 120, and 121. When the subscriber completes his conversation and hangs up his 25 receiver, energizing the supervisory lamp in customary manner, the central operator disconnects or clears out, thereby breaking the ground circuit for the magnet 86 which, becoming deenergized, permits its armature 30 87 to fall back to fully retracted position, so that absolute normal conditions are restored at the subscriber's station. It will be obvious that mechanical release devices may be provided for central station switches 63 35 and 73, releasing said switches when the plug returns to its seat on the table of the switch board, but such contrivances are well known and of obvious adaptability.

While for sufficiency of disclosure, I have 40 fully described in considerable detail a particular embodiment of my invention, it will be apparent to those skilled in the art that numerous changes in the mechanical and electrical arrangement might be made without 45 departure from the spirit of my invention and within the scope of the appended claims.

What I claim is:

1. In a lock-out telephone system, a 50 party line circuit; at each subscriber's station a subscriber's instrument, a step-up device, means to disable the subscriber's instrument when the step-up device is in appropriate position; and at the central station automatic means to actuate said step-up device 55 automatically to complete a cycle of operations; and means to prevent the disabling operation at any selected station.

2. In a lock-out telephone system, the 60 combination of a party line; at each subscriber's station a subscriber's instrument and circuit controlling means therefor; and at the central station calling devices arranged normally to disable the circuit controlling means at each subscriber's station on the party line, 65 and preliminarily settable selective means to

prevent the disabling operation from affecting the circuit-controlling means at the station of any selected subscriber.

3. In a lock-out telephone system, the combination of a party line; at each subscriber's station a subscriber's instrument, a step-up device, means timed by the step-up device to disable the subscriber's instrument, and at the central station means for operating each step-up device through a full cycle 75 of operations, and selective means, timed harmoniously with the subscriber's step-up device for preventing the disabling operation at any selected subscriber's station.

4. The combination with a party line circuit of; at each subscriber's station a talking set ringing means, and step-up devices, arranged to permit disabling of said parts at a predetermined time in a cycle of operations, or at the completion of a cycle of operations to condition the ringer and talking set for functional operation, and at the central station, means for actuating the step-up device, and means timed in harmony with the step-up device normally to permit or 85 selectively to prevent the disabling operation at the time when it may occur at the station of any selected subscriber.

5. The combination with a party line circuit of, at each subscriber's station, a subscriber's instrument, a step-up device, arranged by performance of a complete cycle 95 of operations and the return of its moving parts to normal position to condition said instrument for functional operation, means timed by the step-up device to disable said subscriber's instrument during the cycle of operations of the step-up device; and at the central station means timed harmoniously with the step-up device, operating normally to permit or selectively to prevent the operation of the disabling means at any subscriber's station at the time when it may disable the instrument at that station.

6. The combination with a party line and central station connections, providing distinct operating and controlling circuits, at each subscriber's station a subscriber's instrument, a step-up device, operating means therefor in the operating circuit, controlling means for enabling or disabling the subscriber's instrument to be conditioned for functional operation, timed by the step-up device, a magnet governing said controlling means arranged in the controlling circuit; and at the central station, current-supply means for the responsive device in the operating circuit, and current supply devices for the magnet in the controlling circuit, arranged whereby the governing devices normally permit the disabling operation, and preliminary settable selective means for affecting said controlling circuit to prevent the disabling operation at the station of any selected subscriber.

6 7. In a party line lock-out telephone system, a subscriber's instrument, means at each subscriber's station for operation from normal position through a complete cycle of operations and back to normal to condition the instrument for functional operation, means at the central station automatically to cause such cyclic operation and means controllable from the central station normally to effect the disabling operation upon the instrument set during the cycle of operations of the step-up device, and selectively operable to prevent such disabling operation with respect to the instrument of any desired subscriber.

8. In a lock-out telephone system, at each subscriber's station, an instrument, a step-up device, and a controlling magnet, a switch for conditioning the subscriber's instrument for functional operation, means for locking said switch closed, releasable by the armature of said controlling magnet, and timed as to capability for release by the step-up device, and at the central station means automatically to actuate the step-up device and settable means, operating normally to permit and selectively to prevent such release by the controlling magnet armature during the advancement of the step-up device.

9. In a lock-out party line telephone system, at each station a subscriber's instrument, a step-up device, a switch for the subscriber's instrument, a lock for said switch controlled as to time of release by the step-up device and disabling the subscriber's instrument when released, a controlling magnet having an armature for closing said switch and releasing the lock, having circuit connections closed when said switch is locked, and at the central station, selective means controlling the energization of said magnet at the time when the lock may be released, whereby unlocking of said switch disables the subscriber's instrument and maintenance of the switch locked conditions the subscriber's instrument for operation and conditions the controlling magnet subsequently to effect a release of the lock upon energization of the magnet through the circuit connection maintained closed by the locked switch.

10. In a lock-out party line telephone system, the combination of a line, a cord circuit including ringing connections, step-up means at each subscriber's station each responsive to ringing current, means selectively controlled from the central station and timed by the step-up device of the subscriber's station for enabling or disabling the talking set for functional operation, and means whereby the step-up devices at all the subscribers' stations are returned to normal position upon disconnection of the ringing connection at the central station.

11. In a selective party line telephone system, a line circuit, a cord circuit, and ringing connections therefor, at each subscriber's station a step-up device, a telephone set and controlling means co-operating with the step-up device selectively operable from the central station to condition a desired station to receive a call, means whereby upon disconnection of the ringing connections the step-up devices at all stations are returned to normal position and the controlling devices at all stations except that selectively called are returned to normal position, and whereby upon disconnection of the cord circuit, the controlling device at said selected station is returned to normal condition.

12. In a selective party line telephone system, a line, polarized operating devices connected therewith, a source of alternating current therefor, and means at the central station for impressing a preliminary charge of definite polarity upon the line before the commencement of the alternating current impulses.

13. In a selective party line telephone system, a line, step-up devices at the subscriber's station, a step-up device at the central station, polarized magnets for operating said step-up devices, a source of alternating current supply therefor, means at the central station for impressing a preliminary charge of known polarity upon the circuit for said polarized magnet, before the commencement of transmission of alternating impulses over said circuit.

14. In a selective party line telephone system, a line, subscribers' station apparatus, comprising polarized magnets, central station apparatus comprising polarized magnets, a source of current supply and pole changers for supplying current to the circuits of said polarized devices, and means for starting the operation of the central station polarized devices operating temporarily to disable the pole changer, thereby to insure the impression of a preliminary current charge of known polarity upon the line before the commencement of the alternating impulses through the operation of the pole changer.

15. In a selective party line telephone system, the combination of a line, subscribers' station apparatus, each comprising a step-up device, talking set disabling means timed by the step-up device, and operative by current impulses, means for advancing the step-up device, and central station means for transmitting the disabling impulse during the dwells between steps of the step-up device at the subscriber's station.

16. In a selective party line telephone system, the combination of a suitable line cord, and ringing connections, at each subscriber's station a step-up device, instru-

mental in effecting the selected connection, central station devices for operation in the selection of the desired station, means whereby all step-up devices are returned to normal position when the ringing circuit connections are broken, and whereby all circuit connections are restored to normal upon the clearing out operation, thereby effecting complete restoration of the apparatus at all

subscribers' stations to normal incidental to the ordinary ringing and clearing out operations at the central station.

In testimony whereof I hereunto set my hand in the presence of two witnesses.

NILS EMEL NORSTROM.
